(57) **CLAIM**

The ornamental design for a roof tent as shown and described.

DESCRIPTION

FIG. 1 is a perspective view of a roof tent showing my new design;

FIG. 2 is an in-use perspective view of the roof tent with panels folded and support poles unfolded, for the roof tent shown in FIG. 1;

FIG. 3 is an additional in-use perspective view of the roof tent as shown in FIG. 2;

FIG. 4 is a front view thereof;

FIG. 5 is a back view thereof;

FIG. 6 is a left view thereof;

FIG. 7 is a right view thereof;

FIG. 8 is a top view thereof;

FIG. 9 is a bottom view thereof;

FIG. 10 is an enlarged view of the encircled area 10 of FIG. 1;

FIG. 11 is an enlarged view of the encircled area 11 of FIG. 1;

FIG. 12 is an enlarged view of the encircled area 12 of FIG. 3;

FIG. 13 is an enlarged view of the encircled area 13 of FIG. 4;

FIG. 14 is an enlarged view of the encircled area 14 of FIG. 4;

FIG. 15 is an enlarged view of the encircled area 15 of FIG. 5; and,

FIG. 16 is an enlarged view of the encircled area 16 of FIG. 7.

The broken lines shown on the drawings depict portions of the roof tent that form no part of the claimed design.

1 Claim, 14 Drawing Sheets
